UNITED STATES PATENT OFFICE.

WILLIAM S. THOMAS, OF LOCK HAVEN, PENNSYLVANIA, ASSIGNOR OF ONE-HALF TO
JAMES E. BUZZARD, OF LOCK HAVEN, PENNSYLVANIA.

SPARK-PLUG.

1,221,922.

Specification of Letters Patent. Patented Apr. 10, 1917.

Application filed February 3, 1916. Serial No. 76,027.

To all whom it may concern:

Be it known that I, WILLIAM S. THOMAS, a citizen of the United States, residing at Lock Haven, in the county of Clinton and State of Pennsylvania, have invented certain new and useful Improvements in Spark-Plugs, of which the following is a specification.

My invention relates to improvements in spark plugs, and more particularly to spark plugs designed for use with internal combustion engines, an object of the invention being to so construct the several parts of the plug that the gap between the electrodes can be adjusted without removing the plug, and provide an improved indicator which is located on the upper portion of the plug, and which indicates the gap between the electrodes so that the operator can adjust each plug to suit the working conditions of each cylinder.

A further object is to provide a spark plug of the character stated which permits a relatively wide or fat spark and which is composed of a plurality of parts easily assembled and easily kept clean.

A further object is to provide a spark plug which permits a priming fluid to be poured into the cylinder through the plug, and which under normal conditions is tightly sealed.

A further object is to provide a spark plug of the character described which can be operated to vary the length of gap, and permit the accumulated carbon to be burned whenever desired by simply increasing the length of the gap and the voltage of the electric current.

With these and other objects in view, the invention consists in certain novel features of construction and combinations and arrangements of parts as will be more fully hereinafter described and pointed out in the claims.

45 In the accompanying drawings:

Figure 1 is a view in side elevation illustrating in full lines the normal positions of the several parts, and in dotted lines other positions of adjustment.

50 Fig. 2 is a view in longitudinal section.

Fig. 3 is a top plan view, and

Fig. 4 is a bottom plan view.

1 represents the body of the plug having a cylindrical bore 2, which at its lower end

communicates with a circular recess 3 of 55 larger diameter than the bore 2, and a beveled seat 4 connects the recess 3 with the bore 2 for a purpose which will more fully hereinafter appear.

The body 1 has a screw-threaded end 5 to screw into the engine cylinder (not shown), and a stationary electrode 6 is fixed to the end of body 1, and coöperates with the movable electrode 7 in the ordinary way. This movable electrode 7 is in the form of a 65 rod having a hook shaped lower end 8, which latter and the stationary electrode 6, are recessed as shown at 9, whereby an extended surface is offered to the electric current as it leaps the gap, and insures a fatter spark 70 than is possible with other forms of electrode.

The electrode 7 extends through a ring 10 located in the recess 3, and has a shoulder 11 bearing against the ring, and normally 75 holding the ring against the seat 4 to insure a tight closure of the passage through the plug.

A tube 12, of insulation, preferably fiber, is located in the bore 2, and is spaced from the ring 10 by a series of perforated disks 13, preferably of mica. In other words, the laminated mica disks 13 are positioned between the end of tube 12 and ring 10, and the electrode 7 extends through the ring 10, 80 disks 13, and tube 12, and on its upper screw-threaded end 14, a nut 15 is positioned and operates to bind the shoulder 11 against the ring 10, and securely clamp 85 the electrode in place.

The upper end 14 of the electrode constitutes a binding post, and a nut 16 is positioned thereon to clamp the conductor (not shown) thereto.

The tube 12, at its upper portion, is externally screw-threaded as shown at 20, and two nuts 17 and 18 are located on this threaded portion 20, one nut operating as a jam for the other.

To the lower nut 18, a bifurcated cam 100 lever 19 is pivotally connected, and bears against the end of the body 1, so that this lever operates to move the tube 12 longitudinally in the body 1, and normally holds the tube in one extreme position with the ring 3 tight against the seat 4.

The lever 19 is not only operated to move the tube 12 longitudinally, but also to turn

the tube and vary the gap between the electrodes 6 and 7. To indicate this length of gap, a pointer 21 is fixed to a collar 22 which is secured by a screw 23 around tube 12, and 5 registers with a short scale 24 on the end of body 1, hence indicating exactly the position of the movable electrode.

It will be noted particularly by reference to Fig. 2, that an annular tapering recess 25 10 is provided between ring 10 and the wall of recess 3, and this recess operates as a suction chamber from which any accumulated oil or liquid is sucked out by the movement of the engine piston, hence preventing any 15 accumulation at their point to short circuit the spark plug.

The ring 10 is provided with an annular depending flange 26 which acts as a wall, and prevents the formation of carbon to 20 bridge the gap between the electrodes. In other words, carbon which forms around the electrodes, adjacent the body of the plug, cannot short circuit until accumulated in sufficient quantity to inclose the flanged end 25 of the ring, and this carbon can be readily burned from time to time by simply lengthening the gap between the electrodes and increasing the voltage of the current without removing the spark plug.

30 The priming may be permitted from time to time by swinging the lever 19 on its pivot to the dotted line position shown in Fig. 1, and then pouring the gasoline or other hydro-carbon oil through the bore 2, as it 35 will be noted that the bore 2 is of greater diameter than tube 12, and sufficient space is provided for the passage of the liquid.

The ring 10, however, normally seals the plug, but when moved away from the seat 40 4 by the action of the lever 19, permits the entrance of the liquid into the cylinder.

The parts are so arranged that their movement from time to time dislodges carbon which might otherwise accumulate to short 45 circuit the plug, and it will be noted that the several parts are capable of adjustment to vary the spark and to permit a ready assemblage of the component elements of the plug.

50 Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. The combination in a spark plug, of a body portion having a bore extending therethrough, a tube extending into and having a diameter smaller than the bore thus providing an annular passage around said tube

and extending to the outer surface of the body portion, said body portion having a recess at its innermost end, said recess being of larger diameter than and intersecting said bore, an electrode secured to said tube 70 and having a ring thereon normally fitting said recess and cutting off communication between the bore and the recess, and a single member operative to turn said tube and to raise and lower the tube to move the ring 75 into and out of fitting engagement with said recessed part of the body portion to permit the bore to be brought into open communication with the recess, substantially as described.

2. The combination in a spark plug, of a body portion having a bore extending therethrough, a tube extending into and having a diameter smaller than the bore thus providing an annular passage around said tube 85 and extending to the outer surface of the body portion, said body portion having a recess at its innermost end, said recess being of larger diameter than and intersecting said bore, an electrode secured to said tube 90 and having a ring thereon normally fitting said recess and cutting off communication between the bore and the recess, and a member pivotally supported on said tube and having a cam designed to engage the body portion and thereby move said tube longitudinally to open and close said bore with respect to the recess, substantially as described.

3. The combination in a spark plug, of a body portion having a bore extending therethrough, a tube extending into and having a diameter smaller than the bore thus providing an annular passage around said tube 100 and extending to the outer surface of the body portion, said body portion having a recess at its innermost end, said recess being of larger diameter than and intersecting said bore, an electrode secured to said tube 105 and having a ring thereon normally fitting said recess and cutting off communication between the bore and the recess, said tube being screw-threaded at its outer end, a nut fitting said screw-threaded portion, a lever 110 pivoted on said nut and having a cam operative to move the tube longitudinally when the lever is moved on its pivot, substantially as described.

4. In a spark plug, the combination with 120 a body having a longitudinal bore, and a recess in one end larger than the bore, and a beveled seat connecting the recess and bore, of a tube located in the bore, a ring located in the recess and adapted to engage the 125 seat, a movable electrode projecting through the tube and the ring, a stationary electrode on the body, means for turning the movable electrode relatively to the stationary electrode, said means also adapted to move the 130

movable electrode longitudinally to move the ring away from its seat and permit priming liquid to be poured through the bore of the body, substantially as described.

5. In a spark plug, the combination with a body having a longitudinal bore, and a recess in one end larger than the bore, and a beveled seat connecting the recess and bore, of a tube located in the bore, a ring 10 located in the recess and adapted to engage the seat, a movable electrode projecting through the tube and the ring, a stationary electrode on the body, a lever supported by the tube and having a cam portion for engagement with the body, said lever being adapted to move the tube longitudinally and also adapted to turn the tube, substantially as described.

6. The combination in a spark plug, of a 20 body portion having a bore extending therethrough, a tube extending into and having a diameter smaller than the bore thus providing an annular passage around said tube and extending to the outer surface of the 25 body portion, said body portion having a recess at its innermost end, said recess being of larger diameter than and intersecting said bore, an electrode secured to said tube and having a ring thereon normally fitting said 30 recess and cutting off communication between the bore and the recess, said tube being screw-threaded at its outer end, a nut fitting said screw-threaded portion, a lever pivoted on said nut and having a cam operative 35 to move the tube longitudinally when the lever is moved on its pivot, a second nut on said screw-threaded end of the tube for engagement with the first nut to lock the latter to the tube, said lever when the first 40 nut is locked being operative to turn the tube, substantially as described.

7. The combination in a spark plug, of a body portion having a bore extending therethrough, a tube extending into and having a 45 diameter smaller than the bore thus providing an annular passage around said tube and extending to the outer surface of the body portion, said body portion having a recess at its innermost end, said recess being of larger diameter than and intersecting said bore, an electrode secured to said tube and having a ring thereon normally fitting said 50 recess and cutting off communication between the bore and the recess, the surfaces 55 forming the side wall of the recess and the periphery of said ring being shaped to provide a tapered annular recess between the

ring and said body portion, substantially as described.

8. The combination in a spark plug, of a 60 body portion having a bore extending therethrough, a tube extending into and having a diameter smaller than the bore thus providing an annular passage around said tube and extending to the outer surface of the 65 body portion, said body portion having a recess at its innermost end, said recess being of larger diameter than and intersecting said bore, an electrode secured to said tube and having a ring thereon normally fitting said 70 recess and cutting off communication between the bore and the recess, said ring having a depending flange providing a recess therein wherein carbon may be deposited thus preventing it from spreading, substantially as described.

9. The combination in a spark plug, of a body portion having a stationary electrode, a member rotatable within said body portion and having a movable electrode thereon, a 80 collar carried by said member, a pointer on the collar, means for actuating said member to move the movable electrode toward and from the stationary electrode, said body portion having its outer surface marked and in 85 close proximity to the pointer whereby the latter when the member is moved, will indicate the exact distance between the electrodes, substantially as described.

10. The combination in a spark plug, of a 90 body portion having a bore extending therethrough, a tube extending into and having a diameter smaller than the bore thus providing an annular passage around said tube and extending to the outer surface of the 95 body portion, said body portion having a recess at its innermost end, said recess being of larger diameter than and intersecting said bore, an electrode secured to said tube and having a ring thereon normally fitting said 100 recess and cutting off communication between the bore and the recess, a single member operative to turn said tube and to raise and lower the tube to move the ring into and out of fitting engagement with said recessed 105 part of the body portion to permit the bore to be brought into open communication with the recess, and a plurality of perforated layers of mica interposed between the inner end of said tube and said ring, substantially 110 as described.

WILLIAM S. THOMAS.
